DEODORANT HANGER

Morris Bordman, 4901 Umbria St.,
Philadelphia, Pa. 19127

Filed Feb. 6, 1974, Ser. No. 440,237

Term of patent 14 years

Int. Cl. D8—08

U.S. Cl. D8—246

FIG. 1

FIG. 2

FIG. 3

FIG. 4

FIG. 5

FIG. 6

FIG. 7

FIG. 1 is a perspective view of a deodorant hanger in accordance with the instant invention. A deodorant block is shown in phantom lines for purposes of association.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a top plan view thereof.

FIG. 7 is a bottom plan view thereof.

I claim:

The ornamental design for a deodorant hanger, as shown and described.
